UNITED STATES PATENT OFFICE.

ISAAC P. TURNER, OF TROY, N. Y., ASSIGNOR TO COON & CO., OF SAME PLACE.

CUFF.

SPECIFICATION forming part of Letters Patent No. 255,214, dated March 21, 1882.

Application filed December 10, 1881. (No model.)

To all whom it may concern:

Be it known that I, ISAAC P. TURNER, of the city of Troy, county of Rensselaer, and State of New York, have invented a new and useful 5 Improvement in Apparel-Cuffs, of which the following is a specification.

My invention relates to the form given to the fabric blanks from which apparel-cuffs are made, and the manner in which the blanks are 10 united to produce the cuffs.

My invention consists in the application of the same size in width and length to the linen blank forming the exterior of the cuff as that which is applied to one thickness of the fabric forming the intermediate ply, in combination 15 with another thickness of the latter cut enough wider than the other two to produce a folded box-plait through its longitudinal center, but so that its exterior edges will coincide in width 20 and length with the other two blanks when the plait is formed and folded, the plaited blank having a turning-slit cut in its face near to but inside of the seam where the blanks are border-stitched before being turned, the cuff-facing 25 being formed of two blanks having the same length, but each one having half the width of the exterior linen-blank. To unite the blanks thus relatively cut the unplaited ply-blank is first laid. Next above it is placed the linen exterior blank, and on top of the latter is placed 30 the plaited blank with its plaited side down. Between the latter and the linen blank which forms the finished exterior of the cuff are placed the two half-blanks, with the inner edge of each 35 inserted between the box-plait and the plaited blank, in which position the blanks are border-stitched and turned through the slit in the plaited ply-blank. This being done the loose edges 40 of the half-blanks forming the facing are each secured by a row of stitching passing through the cuff, inside the outer edge of the box-plait, which also lays the latter.

Accompanying this specification and forming 45 a part of it are two plates of drawings containing thirteen figures illustrating my invention, and in all of which the same designation of parts by letter-reference is used.

Figure 1 shows the position relatively of one thickness of the intermediate ply and that of the linen facing when laid preparatory to stitching 50 them to the other parts before the cuff is

turned. Fig. 2 illustrates the ply-blank, which is cut wider than the other blanks shown in Fig. 1 to form a longitudinal box-plait. This figure also shows the position of the turning-slit made in this wider ply-blank, through which the cuff is turned after all the parts are in position and have been border-stitched. Fig. 3 illustrates the blank shown in Fig. 2 as folded through its longitudinal center, and a line of 60 stitching run far enough from the edge of the fold to form a box-plait. Fig. 5 shows in a cross-section the box-plait in part opened out, and Fig. 4 shows in a cross-section the blank and plait with the latter in part folded. Figs. 65 6 and 7 illustrate the half-blanks, which, with the central box-plait, form the cuff-facing when the parts are border-stitched and turned. Fig. 8 shows in a cross-section the position of the plaited ply-blank and the half-blanks, with the 70 inner edges of the latter placed between the fold of the plait and the plait-blank, and as arranged when, with the plait side down, they are placed on the blanks shown in Fig. 1 before being border-stitched and turned. Fig. 9 illustrates the relative position in a cross-section of all the blanks after having been laid and border-stitched before being turned through the slit cut in the plaited ply-blank. Fig. 10 shows the cuff after having been border-stitched 80 and turned, and before having been stitched along the edges of the box-plait to lay the latter, and to secure the inner loose edges of the half-blanks which, with the box-plait, form the cuff-facing, the loose inner edges of the half-blanks in this latter illustration being designated by a dotted line. Fig. 11 shows a cross-section taken on the line D D of Fig. 10. Fig. 12 illustrates the completed cuff; and Fig. 13, a cross-section of the same, taken on the line 90 y y of Fig. 12. In all the figures showing cross-sections the thickness of the blanks is much exaggerated to better illustrate their relative position.

As shown in the drawings, the several parts 95 of the cuff illustrated are designated by letter-reference as follows, and the manner of uniting them thus described.

The letter A designates a thickness of the 100 ply; B, the linen exterior; and these are laid, as shown in Fig. 1, with the latter over the former.

The letter C denotes a ply-blank cut enough wider than the two others named to produce through its longitudinal center a box-plait, and having near its outer seaming-edge the 5 turning-slit O. This latter blank C, as shown in Fig. 3, is folded through its longitudinal center, and the line of stitching d runs far enough from its folded edge to produce a box-plait, and which is opened out and folded, as shown 10 in Figs. 5 and 4.

The letters a a, Figs. 6 and 7, designate the two half-blanks, which, with the box-plait C'', form the facing of the cuff when finished. These half-blanks a a are placed with their inner edges loosely laid or temporarily pasted 15 between the side folds of the box-plait C'' and the ply C, from which the latter is folded, as shown in cross-section at Fig. 8. The plaited ply-blank and the half-blanks are then laid on 20 the blanks B and A, as positioned in Fig. 1, with the half-blanks and the plaited side of the ply-blank C down, in which condition as laid and placed they are border-stitched, the parts appearing relatively as shown in a cross- 25 section at Fig. 9. The parts are then turned through the slit O made in the plaited ply-blank C, which brings out the blank B as the exterior of the cuff, and the half-blanks a a and the box-plait C'' as forming the facing of 30 the cuff, with the inner edges of the half-blanks unattached to the plait which they are beneath, and loose for adjustment. After the adjustment the inner edges of the half-blanks a a are connected to the box-plait C'' by the 35 rows of stitching s³s⁴, as shown in Figs. 12 and 13 of the drawings. In all the cross-sections the thicknesses of the fabric are necessarily exaggerated to better illustrate them and to give distinctness. The application of a longitudinal box-plait thus formed in one of the 40 ply-blanks and the use of two half-blanks to produce the facing furnish a means for a cross-adjustment from the sides to the center, and which may be made before securing the 45 parts, and so as to remove any slack or distortion, and thus prevent the facing from wrinkling when being laundered and ironed, and at the same time, by means of the added box-plait, to secure and stay the parts at their longitudinal center in a new and useful manner. 50

While I have described and shown my invention as applied to a cuff having rounded corners, it can as an entirety be also applied to one having square corners, and to produce 55 a three-ply cuff by omitting the use of the filling ply-blank A, the other parts remaining the same as are shown and described.

I am well aware that it is not new to stitch

cuffs through their longitudinal center, and I make no claim to such an application apart 60 from its connection with the box-plait and the two half-blanks which I employ.

Having thus described my invention, what I claim, and desire to secure by Letters Patent, is—

65

1. In an apparel-cuff, the combination of a fabric ply-blank having a central longitudinal box-plait and a turning-slit in its face inside of the edge where sewed to be turned, an exterior fabric blank of the same width and length 70 as the ply-blank when its box-plait is folded, two fabric facing half-blanks having the same length as the exterior blank, but half its width, and the aforesaid parts united by placing the exterior blank next to the plaited face of the 75 ply-blank, and then inserting between them, on each side of the box-plait, one of the facing half-blanks, with its inner edge beneath the fold of the box-plait, then border-stitching the parts as placed, turning them through the slit 80 in the plaited ply-blank, and stitching them longitudinally along the edges of the box-plait to secure the inner edges of the half-blanks and around the edge of cuff, as shown and described. 85

2. In combination, in an apparel-cuff, the

90

exterior fabric blank B, the fabric ply-blank A,

95

the fabric ply-blank C, the latter having the

100

longitudinal box-plait C'', and the turning-slit

105

O, the two fabric facing half-blanks a a, and

110

the aforesaid parts united by first laying the

115

ply-blank A upon this the exterior blank C,

120

with its plaited side down and one of the fac-

125

ing half-blanks inserted next beneath the blank

130

C, upon each side of the box-plait, and its in-

135

ner edge beneath the fold of the box-plait, the

140

parts in this position being border-stitched

145

and turned through the slit O and stitched

150

along the edges of the half-blanks and around

155

inside of the cuff edge, as shown and described.

3. In an apparel-cuff, a cuff-facing, in com- 160

bination, consisting of the two fabric half- 165

blanks a a, the box-plait C'', and the latter

170

formed on a thickness of the intermediate fill-

175

ing ply, with the inner edges of each one of the

180

half-blanks beneath one of the plait-folds, and

185

the rows of stitching s³s⁴ connecting the in-

190

ner edges of the half-blanks with the plait and

195

ply on which the plait is formed, as shown and

200

described.

Signed at Troy, New York, this 8th day of 205

December, 1881.

ISAAC P. TURNER.
